UNITED STATES PATENT OFFICE.

WILLIAM C. BACKOF, OF CHICAGO, ILLINOIS.

DESIGN FOR A COIN-CONTROLLED ELECTRIC-MACHINE CASE.

SPECIFICATION forming part of Design No. 31,839, dated November 14, 1899.

Application filed April 24, 1899. Serial No. 714,338. Term of patent 7 years.

To all whom it may concern:

Be it known that I, WILLIAM C. BACKOF, a citizen of the United States, residing at Chicago, in the county of Cook and State of Illinois, have invented and produced a new and original Design for Coin-Controlled Electric-Machine Cases, of which the following is a specification, reference being had to the accompanying drawings, forming part thereof, in which—

Figure 1 is a perspective view, and Fig. 2 a front elevation, of my design.

As shown by the drawings, the leading or material feature of my design consists of a base A, a pedestal B, supported thereon, and a square frame C, supported upon the face of the pedestal, the corners c' c^2 being located in a vertical central line with the base and the pedestal and the corners c^3 c^4 thereof being located upon a horizontal line, a circle D being described with the point of intersection of said lines as a center thereof.

A square border H, in this instance com-

posed of circles, is arranged in lines within and parallel to the sides of the frame C, and a circle of radial graduations E is marked upon the face outside of the circle D and within the said border. 25

A rectangular box E', mounted on the base and placed back of the pedestal and square frame to be covered thereby, is used to contain the mechanism. 30

The handles F project outside of the case, the corners of the frame thus serving to approximately indicate the distance moved in 35 the arc of a circle relatively thereto.

Having described my invention, what I claim as new, and desire to secure by Letters Patent, is—

The design for a coin-controlled electric-machine case, as herein shown and described. 40

WILLIAM C. BACKOF.
